(57) **CLAIM**

The ornamental design for a product package for absorbent articles, as shown and described.

DESCRIPTION

FIG. 1 is a perspective view of a first embodiment showing a top, right side, and front views of a product package for absorbent articles;

FIG. 2 is a top view of the embodiment of the package shown in FIG. 1;

FIG. 3 is a front view of the embodiment of the package shown in FIG. 1;

FIG. 4 is a bottom view of the embodiment of the package shown in FIG. 1;

FIG. 5 is a back view of the embodiment of the package shown in FIG. 1;

FIG. 6 is a left side view of the embodiment of the package shown in FIG. 1; and

FIG. 7 is a right side view of the embodiment of the package shown in FIG. 1.

FIG. 8 is a perspective view of a second embodiment showing a top, right side, and front views of a product package for absorbent articles;

FIG. 9 is a top view of the embodiment of the package shown in FIG. 8;

FIG. 10 is a front view of the embodiment of the package shown in FIG. 8;

FIG. 11 is a bottom view of the embodiment of the package shown in FIG. 8;

FIG. 12 is a back view of the embodiment of the package shown in FIG. 8;

FIG. 13 is a left side view of the embodiment of the package shown in FIG. 8; and,

FIG. 14 is a right side view of the embodiment of the package shown in FIG. 8.

Broken lines are included for the purpose of illustrating environment and form no part of the claimed design.

1 Claim, 8 Drawing Sheets
